UNITED STATES PATENT OFFICE.

DAVID C. LARSON, OF YONKERS, NEW YORK, ASSIGNOR TO OTIS ELEVATOR COMPANY,
OF JERSEY CITY, NEW JERSEY, A CORPORATION OF NEW JERSEY.

ELEVATOR-CONTROLLING APPARATUS.

1,286,358.

Specification of Letters Patent.

Patented Dec. 3, 1918.

Application filed March 29, 1917. Serial No. 158,481.

To all whom it may concern:

Be it known that I, DAVID C. LARSON, a citizen of the United States, residing in Yonkers, in the county of Westchester and 5 State of New York, have invented a new and useful Improvement in Elevator-Controlling Apparatus, of which the following is a specification.

This invention relates to improvements 10 in control apparatus for elevators, it being directed more particularly to mechanism selectively to time the operation of the elevator car, this mechanism being commonly known as automatic push-button mechanism.

It is well known that car hoisting ropes or cables stretch more or less in accordance with the load on the car platform, and with the initial adjustment of the timing mechanism or floor controller which in standard practice is such as to stop the car level with the landing for an average car load, a heavily loaded car will, because of the stretch of the cable, stop short of or below 25 the landing in ascending, and run past the landing in descending. However, according to the present invention, this difficulty is overcome by providing a connection between the car and floor controller apparatus, 30 whereby the latter is adjusted more or less in accordance with the stretch of the hoisting cables. With this improved arrangement the floor controller will act automatically to shut off the motive power and apply the car brake, later with a heavy load ascending and earlier with a heavy load descending, as compared with the original adjustment for the average car load, the effect being to stop the car level with the 40 floor landing.

In the accompanying drawings, Figure 1 illustrates in a more or less diagrammatic manner, a typical electric elevator system embodying automatic push button controlled apparatus, arranged in accordance with the present invention: Figs. 2 and 3 illustrate somewhat in detail and in different views, the floor controller mechanism; Fig. 4 illustrates diagrammatically, the 45 invention as embodied in a traction elevator system; Figs. 5 and 6 illustrate diagrammatically the invention in modified forms; and Figs. 7 and 8 illustrate in different views, a floor controller mechanism of a 55 modified construction such as is used in the

modified embodiment of the invention as illustrated in Fig. 6.

Referring now to Fig. 1, it comprises an elevator car C, and a car counterweight A connected to hoisting cables 1, which are attached to a hoisting drum 2. The hoisting drum 2 is operable by the electric motor M, through the intermediary of a worm and gear connection 3. An electro-mechanical brake of a well known type is designated B. 60

Electro-magnetic reversing switches to control the motor M are designated R, R', R controlling the motor for descending direction of car travel, and R' for ascending direction of travel. 70

The automatic push button apparatus comprises car push buttons 4, 4', 4'', hall push buttons, 5, 5', 5'', floor relay magnets 6, 6', 6'', a non-interference magnet 7, car holding magnet 8, door contacts 9, and the 75 floor controller F, the principle of operation of the latter being better understood by the diagrammatic illustration thereof, as in Fig. 1, the actual construction being as illustrated in Fig. 3, which construction is well 80 known and substantially like that illustrated in the patent to E. R. Carichoff, No. 783,174.

The floor controller illustrated in Figs. 2 and 3, briefly stated, comprises a shaft 10 operable in unison with the movement of the elevator car through the intermediary of gearing 11, and other connections herein-after described. Rocker arms 12, 12', 12'', 12''', are carried by the rock shaft 10, these arms being adapted to actuate switches 13, 13', 13'', 13''', respectively. The switches 13, 13'', control the car in descending, being opened by their respective arms when rocked in an anti-clockwise direction, which corresponds to descending direction of car travel, 95 and closed by movement of the said arms in a clockwise direction. Switches 13', 13''' control the car in ascending, being opened by their respective arms when the latter rock in a clockwise direction, and closed 100 by rocking of said arms in an anti-clockwise direction. It will be mentioned that one switch each is provided for the bottom and top landings L, L'', two of these switches being provided for an intermediate landing L'. 105

Each switch such as 13, for example, comprises a pair of separated depending contact strips 14, 14', secured to, but insulated from the controller framework 15. A 110

conductor such as 16 is adapted to bridge the strips 14, 14', and thereby close-circuit the said contacts. The conductor 16 is carried by, but insulated from an arm 17 5 adapted to rock on a fixed rod 18. The arm is provided with a member such as 19, through the intermediary of which the arm is rocked in reverse directions by engagement with a roller 20 carried by the rocker 10 arm 12.

The rocker arms 12 are originally adjusted so as to open their respective switches when the car approaches within a predetermined distance of the landing, the effect 15 being to disconnect the motor M from its source of supply and effect an application of the brake B. After the above operation takes place, the car has a tendency to coast some distance more or less, due to the momentum of the moving parts, and hence this 20 initial adjustment of the arms, will for the average car load, allow of the coast of the car and bring the car to stop substantially level with the floor landing. However, 25 since for a heavily loaded car, the coast thereof is less for ascending and greater for descending than that of a car with an average load, and considering in addition to this the stretch of the cable due to the heavy 30 load on the car platform, it will be seen that the original adjustment will for the heavy load condition result in the car stopping some distance below the floor landing.

In order automatically to adjust the 35 rocker arms in accordance with this stretch or elongation of the hoisting cables 1, I provide an auxiliary rope or cable 21, one end being connected to the elevator car, and the other to a weight 22. The auxiliary 40 cable connects with a lever 23 at an intermediate point 24 thereon, the back drum counterweight cable 1' forming a fulcrum at 25 on which the lever 23 is adapted to rock. A cable or chain 26 forms a connection 45 whereby the rock shaft 10 of the floor controller is moved in unison with the movement of the elevator car. This cable or chain has one end connected to any desired one of the points 27, on the lever 23, the 50 cable or chain engaging a sheave or sprocket wheel 28, which actuates the rock shaft 10 through the intermediary of the gearing 11. A weight 30 which may be constructed to encircle the cables 21 and 1, is secured to 55 the opposite end of the cable or chain 26, this weight being somewhat overbalanced by the action of the weight 22.

The diagrammatic illustration of the floor controller in Fig. 1, consists of two contact 60 segments 31, 32, adapted to make contact with stationary brushes 33, 34, 35, 36 and 37, the brushes 33 and 34, being connected to the windings of the reversing switches R, R', respectively. The contact segments 65 may be mounted upon a suitable insulating

base and rotated in unison with the movement of the elevator car through the connection heretofore described in connection with Figs. 2 and 3.

The operation will now be described, and 70 since the system of circuits are well known, they will be described only briefly.

In Fig. 1, the car is at rest at the second floor, the operating circuit being broken at the brush 36 of the floor controller. Let it 75 be assumed that the hall-button 5" at the floor landing L" is pressed, this closing a circuit for the winding of the reversing switch R' as follows: + main, wire 38, door contacts 9, through the two windings of the 80 non-interference magnet 7, contacts 39, wire 40, button 5", wires 41, 42, winding of floor relay 6", wire 43, brush 37, segment 32 to brush 34, wire 44, thence through winding of reversing switch R' to - line. 85

The reversing switch R' will now close and effect the release of the brake B and operation of the motor M to operate the car in an ascending direction. Operation of the car in an ascending direction effects rotation of the sheave or sprocket 28 in a counter-clockwise direction, the segments 31, 32 which correspond to the rock shaft 10 of Figs. 2 and 3, being rotated in a reverse or clockwise direction. Thus when the elevator car approaches within a predetermined distance of the landing L", the operating circuit is opened by the segment 32 disengaging the brush 37. In this manner 90 the circuit to the reversing switch winding R' is opened and the reversing switch will open and disconnect the motor from its source of power supply and effect application of the brake to retard and stop the car. From the above description it will be seen 95 that the floor controller functions to control the car in its movement after a button is pressed and to automatically stop the car at the desired floor landing, the floor controller functioning in a similar manner by pressing 100 a car push-button. 105

For descending direction of car travel, the contact segments 31, 32 and rock shaft 10 will rotate in an anti-clockwise direction.

Coming now to the action of the improved connection automatically to adjust the contact segments or rock shaft 10, in accordance with the stretch of the cable, let us assume a heavy load on the car platform. This 115 causes a stretch of the hoisting cables 1 extending between the car and hoisting drum. The movement of the car imparts movement through the cable 21 to rock the lever 23 in a counter-clockwise direction. This movement of the lever 23 is taken up by the 120 weighted cable or chain 26, which effects rotation of the sheave or sprocket wheel 28 in a clockwise direction, and consequently the segments 31 and 32, on the rock shaft 10 125 will be rotated in an anti-clockwise direction. 130

Hence assuming again the initial adjustment of the brushes and contact segments to be as in Fig. 1, the automatic adjustment as caused by the stretch of the cable, will rotate the segments 31, 32, in an anti-clockwise direction, so that for ascending direction of car travel the segment 32 will disengage the brushes 36 and 37 later than with the original settings and for descending direction of car travel, the adjustment will cause the brushes 35 and 36 to disengage the segment 31 sooner than with the original setting.

The movement imparted to the contact segments 31, 32 or the rock-shaft 10, due to the stretch of the hoisting cable may be varied more or less, by changing the point of connection of the cable or chain 26, on the lever 23, relatively to the fulcrum point 25, and it will thus be seen that means are provided to over-compensate for the stretch of the hoisting cable 1.

In Fig. 4 a typical traction driven elevator is illustrated, the car hoisting cables 1, supporting the car C at one end thereof and the counterweight A at the other end, the cables passing around the traction sheaves 45 in the usual manner. In this arrangement movement of the car due to the stretch or elongation of the hoisting cables 1, imparts movement through the cable 21 to rock the lever 23 in a counter-clockwise direction this movement being taken up by the weighted cable or chain 26, which effects rotation of the sheave or sprocket wheel 28 in a counter-clockwise direction. Since the adjustment in this arrangement effects rotation of the sheave or sprocket wheel 28 in a direction reverse to that of Fig. 1, it is therefore necessary in order that the floor controller function as in Fig. 1, to interchange the connections to the brushes 33 and 34, and also to the brushes 35 and 37.

In Fig. 5, the car C is connected by the hoisting cable 1 to the hoisting drum 2, adapted for operation through the worm and gear connection as illustrated in Fig. 1. The car or back drum counterweight is designated A. In this arrangement the stretch or elongation of the hoisting cable 1 acts through a chain or cable 43 to adjust or actuate the sheave or sprocket wheel 28 directly, the chain or cable having one end connected directly to the car, and the other end carrying a weight 46.

In Fig. 6 the car hoisting apparatus is similar to that illustrated in Fig. 1. The floor controller F is of a modified construction as illustrated in Figs. 7 and 8, whereby the adjustment thereof is effected by means of a standing cable 47, the framework 13 carrying the fixed contacts being adapted to rock on the shaft 10, and the sprocket wheel 28 which operates the latter, being connected as in the usual manner to the hoisting drum shaft 2' by a sprocket and chain connection

43. Movement of the car due to stretch of the hoisting cable 1 rocks a lever 50 fulcrumed at 51 to the back counterweight cable 1' through the intermediary of a cable 52 connected to the car. The lever 50 carries a roller 53 which coacts with the standing cable, the lever through its rocking movement actuating the standing cable to rock the controller frame 13 against the action of a weight 54. It is obvious that the results 75 accomplished by this construction are the same as with the constructions heretofore described.

Having thus described the invention, and without limiting myself to the precise details of construction and arrangements of parts, what I claim is new and desire to secure by Letters Patent of the United States, is:

1. In hoisting apparatus, the combination with the car, a car hoisting cable, a motor to operate the car, a brake, a push button system of circuits and a floor controller to control the motor and brake, and means to operate the floor controller in unison with the car and to effect adjustment of the floor controller in accordance with the stretch of the hoisting cable.

2. In hoisting apparatus, the combination with the car, means to operate the car, controlling mechanism having permanent adjustment to time the operation of the car and automatically stop the same at a predetermined point, and means to vary the timing operation of the controlling mechanism and effect the stopping operation later for an ascending load and earlier for a descending load, as compared with the timing operation effected by the permanent adjustment.

3. In hoisting apparatus, the combination with the car, means to operate the car, controlling mechanism having permanent adjustment to time the operation of the car and automatically stop the same at a predetermined point, and means responsive to the load to vary the timing operation and effect the automatic stopping operation later for an ascending load and earlier for a descending load, as compared with the timing effected by the permanent adjustment.

4. In hoisting apparatus, the combination with the car, means to operate the car, a car hoisting cable, controlling mechanism having permanent adjustment to time the operation of the car, automatically to stop at a predetermined point, and means operable in accordance with the stretch of the hoisting cable to vary the timing operation and effect the automatic stopping operation later for an ascending load and earlier for a descending load, as compared with the timing effected by the permanent adjustment.

5. In hoisting apparatus, the combination with the car, motive means to operate the

car, a hoisting cable, a push button system of circuits and a floor controller to control the motive means, a lever fulcrumed on the hoisting cable, and operatively connected to the floor controller, and means to actuate the said lever in accordance with the load on the car.

6. In hoisting apparatus, the combination with the car, motive means to operate the car, a hoisting cable, a push-button system of circuits and a floor controller to control the motive means, a lever fulcrumed on the hoisting cable and operatively connected to the floor controller, and means to actuate the said lever in accordance with the stretch of the hoisting cable.

7. In hoisting apparatus, the combination with the car, motive means to operate the car, a hoisting cable, a push button system of circuits and a floor controller to control the motive means, a lever fulcrumed on the hoisting cable and operatively connected to

the floor controller, and a flexible connection between the car and the said lever operable to rock the said lever.

8. In hoisting apparatus, the combination with the car, motive means to operate the car, a hoisting cable, a push button system of circuits and a floor controller to control the motive means, a lever fulcrumed on the hoisting cable, a flexible member connecting the lever and floor controller to actuate the latter in unison with the car, and a flexible member connecting the car and the said lever, operable to rock the latter in accordance with the load on the car.

In testimony whereof I have signed my name to this specification in the presence of two subscribing witnesses.

DAVID C. LARSON.
